UNITED STATES PATENT OFFICE.

HENRY PENNINGTON, OF PHILADELPHIA, PENNSYLVANIA.

DESIGN FOR AN ADVERTISING-CARD.

SPECIFICATION forming part of Design No. 13,367, dated October 24, 1882.

Application filed September 11, 1882. Term of patent 7 years.

To all whom it may concern:

Be it known that I, HENRY PENNINGTON, a citizen of the United States, residing at the city of Philadelphia, in the county of Philadelphia and State of Pennsylvania, have invented and produced a new and original Design for Advertising-Cards, of which the following is a specification, reference being had to the accompanying drawing, forming part thereof.

- 10 The most prominent feature of my said design consists of the representation on a flat surface of a cup in its saucer. The cup has a handle on the side to the right and in front of the cup, and resting against it is a spray of a 15 wild rose bush having leaves and flowers and extending to the saucer. Resting on said spray are two oblong cards, diagonally placed, and attached to each other by means of a ribbon tied in a bow, the larger of said cards being 20 on the left and containing within a border a landscape. In the foreground of said landscape are represented three negro women and one negro boy gathering fruit from a tall shrub or bush, while a forest is shown in the distance. 25 The other card is plain, and has a dark ground.

It will readily be understood that the cup, saucer, spray of a wild rose bush, and also the landscape on the larger card may be represented in appropriate colors, and also that the card, which in the drawing is represented as plain, is intended to contain any desired advertising-matter; or the same may be printed across the face of the design or on its back.

The design herein described, in preparing it as an article of manufacture, will, with a die 35 or otherwise, be cut out of the card or other material on which it shall be printed in the shape of a cup and saucer, so as to appear as nearly as possible like the things that it represents.

I claim—

The design for advertising-cards, consisting of the representation of a cup and saucer, spray, two cards, and said landscape, as shown and described.

HENRY PENNINGTON.
